JAMES H. REED, OF SWAMPSCOTT, MASSACHUSETTS, ASSIGNOR, BY MESNE ASSIGNMENTS, TO THE LITTLEWAY PROCESS COMPANY, OF LYNN, MASSACHUSETTS, A CORPORATION OF MASSACHUSETTS.

SHOE AND METHOD OF MAKING THE SAME.

Application filed January 22, 1921. Serial No. 439,254.

To all whom it may concern:

Be it known that I, JAMES H. REED, a citizen of the United States, residing at Swampscott, county of Essex, State of Massachusetts, have invented a certain new and useful Improvement in Shoes and Methods of Making the Same, of which the following is a specification, reference being had therein to the accompanying drawings.

10 My invention relates to the manufacture of boots and shoes and has for its object a shoe which can be more cheaply constructed than shoes heretofore in use and which shall have the durability and possibilities of repair heretofore found chiefly in so-called Goodyear welt shoes.

Heretofore, machine-made shoes have been chiefly of three types—(1) the turn shoe, (2) the Goodyear welt shoe, and (3) the 20 McKay shoe. As is well understood by those skilled in the art, turn shoes are limited to shoes constructed of light flexible materials capable of being turned inside out during the process of manufacture. Good-year welt shoes are the most durable and satisfactory construction, particularly for heavy shoes, as they wear much longer than either of the other two types and are capable of repeated repair, methods of repairing 25 having been devised by which the shoe can be restored to almost its original condition. Goodyear welt shoes are, however, relatively expensive to manufacture on account of the number and intricacy of the processes to 30 which they must be subjected during manufacture.

The McKay shoe can be constructed to have the general appearance of the Good-year welt shoe and is much cheaper to manufacture but is not durable, and not capable of repeated repair because if resewn the insole is cut by the needle and thread. Furthermore, McKay shoes are not as comfortable to wear because they are stiff and rigid 45 and the interior of the shoe is not left in a perfectly smooth condition. The chief reason why the McKay shoe is not durable is because the outsole is stitched to the upper and insole by a chain stitch located 50 within the shoe, and the seam is of such a character that as the shoe is worn, the threads composing the stitches are cut off and the repeated bending of the sole to which the shoe is subjected when worn, soon

pulls the ends of the thread through the 55 outsole so that the shoe goes to pieces. This is due in part to the fact that a needle which is large in relation to the thread must be employed in making a chain stitch. In repairing the shoe, the new outsole is usually 60 nailed over the old one, but the weakness due to the fact that the ends of the thread have been cut off, is still inherent in the shoe, unless the nails are clinched on the inside. The use of nails is of course very 65 objectionable. The chief cause of the stiffness of McKay shoes is the chain stitch which always renders the shoe less flexible than a lock-stitch seam.

My invention, therefore, consists in securing together the parts of a shoe constructed like a McKay shoe with a through and through lock stitch seam formed with two threads, the locks of the stitches being located in the outsole so that when the shuttle thread is worn off, the sole is still held to the insole and upper by means of the cop thread. In this way a shoe can be manufactured at a saving of expense amounting to from 25 to 50 cents per pair, which will closely approximate in durability a Goodyear welt shoe and which can be repeatedly repaired, because the stitching does not cut the insole to pieces sufficiently to prevent resewing. A specific form of my invention 85 also consists in stitching a half soled shoe with a lock-stitch machine along the rear edge of the half sole.

The invention will be fully understood from the following description when taken 90 in connection with the accompanying drawings, and the novel features thereof will be pointed out and clearly defined in the claims at the close of this specification.

In the drawings, Fig. 1 is a bottom plan 95 view of the toe end of a shoe embodying my invention.

Fig. 2 is a section on line 2—2.

Fig. 3 is a section taken longitudinally 100 of the seam.

In Figures 2 and 3, the parts are exaggerated and distorted for clearness of illustration.

Referring now to the drawings, at 1 is shown the outsole of the shoe, at 2 a half 105 sole, at 3 the insole, and at 4 the upper. The half sole of the shoe is grooved or scratched in the usual way, as shown at 15,

face. The stitching 7 is formed with an upper or cop thread 5 and a lower or shuttle thread 6, and the two threads are inter- 35
all secured together by a through-and-through, two-thread, lock-stitch seam located inside the shoe.

5 woven with each other to form a lock stitch. The stitches are drawn down with tension sufficient to position the lock 8 well below the surface of the half sole, if there is one, or of the outsole if no half sole is 10 employed so that the sole may be worn through without danger that the parts of the shoe will pull apart. The shoe shown in the drawings is also stitched with a lock-stitching across the rear edge of the half 15 sole, as shown at 9, to take the place of the nails which are usually inserted along this line.

10 The results attained by the herein described simple change in construction of the 20 McKay shoe are very remarkable, both in the reduced cost of manufacture and the improvement in the quality of the shoe which is produced.

What I claim is:—

25 1. The herein described shoe having an insole, an outsole, and an upper secured together by a through-and-through, two-thread, lock-stitch seam located inside the shoe.

30 2. The herein described shoe having an insole, an outsole, and an upper with an inturned edge interposed between the edges

35 of said insole and outsole, said parts being all secured together by a through-and-through, two-thread, lock-stitch seam located inside the shoe and the thread locks of which are located within the outer surface of said out-sole.

40 3. The herein described shoe having an insole, an outsole, and an upper secured together by a through-and-through, two-thread, lock-stitch seam located inside the shoe and the thread locks of which are located within the outer surface of said out-sole.

45 4. The herein described shoe having an insole, an outsole, and an upper, the edge portions of all of said parts being secured together substantially throughout their 50 lengths about the forepart of the shoe by a through-and-through, two-thread, lock-stitch seam located inside the shoe.

50 5. The herein described shoe having an insole, an outsole, and an upper with an in-turned edge interposed between the edges of said insole and outsole, the edges of all of said parts being secured together sub-55 stantially throughout their lengths about the forepart of the shoe by a through-and-through, two-thread, lock-stitch seam located inside the shoe and the thread locks of which are located within the outer surface of said outsole.

In testimony whereof I affix my signature.

JAMES H. REED.
